UNITED STATES PATENT OFFICE.

MAXIMILIAN ROBERT LAWRENCE, OF MANCHESTER, ENGLAND.

CARBURETER FOR INTERNAL-COMBUSTION ENGINES.

1,088,231.

Specification of Letters Patent. Patented Feb. 24, 1914.

Application filed April 16, 1913. Serial No. 761,504.

To all whom it may concern:

Be it known that I, MAXIMILIAN ROBERT LAWRENCE, a subject of the King of Great Britain, and residing at Manchester, in the county of Lancashire, England, motor-car dealer, have invented certain new and useful Improvements in Carbureters for Internal-Combustion Engines, of which the following is a specification.

10 This invention relates to carbureters for internal combustion engines of the type in which air, which passes transversely across the liquid fuel supply inlet, and the liquid fuel supply, is controlled by a weight valve 15 which operates in an inclined direction and is constantly under the influence of the engine suction through the medium of a flexible device operating on the bellows principle; and has for its objects to avoid any 20 risk of air from the outside being drawn into the interior of the said flexible device, and to facilitate the assembling of parts of the apparatus.

In order that the invention may be clearly 25 understood, I will describe the same by reference to the accompanying drawing.

In this drawing, A is the carbureting chamber, B the weight valve which is carried to move in an inclined direction, and 30 besides controlling the supply of air which enters the air inlet a, carries at its lower end a needle valve C which controls the supply of liquid fuel through the nozzle C'. The valve B is fixed on the lower end of 35 a valve-stalk B', which is just a sliding fit through the base D¹ of a chamber D within which is contained a bellows device E through the medium of which the valve B is influenced by the suction of the engine.

40 The stalk B' has an axial passage-way b' which is open at its outer end to the interior of the bellows E, and at its inner end communicates with a transverse passage b formed in the valve B. These passage-ways 45 form the sole means of communication between the interior of the bellows device E and the carbureting chamber A. The inner end of the flexible wall e of the bellows device is securely fixed, in an air-tight manner, around a disk-shaped end b² of the stalk B¹, and the outer end of such wall is correspondingly fixed in relation to the outer end of the chamber D which contains the bellows device. The outer end of the 50 flexible wall of the bellows device is securely fixed around a disk e' which is sepa-

rately-formed from the outer end of the chamber D, and is so fixed prior to the disk e' being fixed against the inner face of the outer end of the chamber, such as by a bolt 60 and nut e². The stalk B¹ is not carried as heretofore through the bellows device and through the back end of the chamber D, as this is not found to be necessary. The wall d and back end d' of the chamber D are 65 formed integral with one another.

In putting the parts together, the flexible wall e of the bellows device is first secured, in a manner well understood, around the disk e'. The disk e' is then fixed against 70 the inner face of the end d' of the chamber D; then the bellows device is securely fixed around the disk b² of the valve-stalk, and then the portion of the apparatus which consists of the wall d, and back end d' of 75 the chamber D, the bellows device, and the valve-stalk, is put into place by passing the valve stalk down through the base D¹ of the chamber D, and bringing the inner edge of the wall d around a bung d² of the base 80 D¹. The cover, constituted by the wall d and end d' of the chamber, may be held securely to the base D¹ in any convenient manner, such as by means of spring clips, of which one, F, is shown. The clip F is 85 pivoted to a lug a' of the carbureter casting, and is shaped to snap over a fillet or bead d³ which runs around the back end d' of the cover. Two of these clips would be used in positions opposite to one another 90 around the cover, and as the other clip could not conveniently be used in position opposite to the one shown, the clip which is shown would be placed in a somewhat different position around the cover, as will 95 be obvious.

The cover or removable portion of the chamber constituted by the wall d and back end d' may be formed in one piece of sheet metal by drawing it between dies. 100

Having fully described my invention, what I claim, and desire to secure by Letters Patent, is:—

1. In a carbureter for an internal combustion engine, a weight valve operating in 105 an inclined direction to control both the passage-way for air which passes transversely across the liquid fuel opening to the mixing chamber, and the liquid fuel supply into such chamber, a flexible device of the bellows type connected with said valve and controlling the movements of said valve 110

under the influence of the engine suction, and a passage-way which passes through the inner end of the flexible device and through the weight valve and communicates with the 5 passage-way for combustible mixture to the engine.

2. In a carbureter for an internal combustion engine, a weight valve operating in an inclined direction to control both the 10 passage-way for air which passes transversely across the liquid fuel opening to the mixing chamber, and the liquid fuel supply into such chamber, a flexible device of the bellows type connected with said valve 15 and controlling the movements of said valve under the influence of the engine suction, a spindle of such valve which connects directly with the inner end of the said flexible device and a passage-way which extends 20 from the inner end of the flexible device through the weight valve spindle and communicates with the passage-way for combustible mixture to the engine.

3. In a carbureter for an internal com-

bustion engine, a weight valve operating in 25 an inclined direction to control both the passage-way for air which passes transversely across the liquid fuel opening to the mixing chamber and the liquid fuel supply into such chamber, a bellows device connected with said valve and controlling the movements of said valve under the influence of the engine suction, a passage-way which extends from the inner end of the bellows device and communicates with the passage-way for the combustible mixture to the engine and a casing which surrounds the bellows device and is formed with the back end and wall integral with one another and is removably clamped down around a fixed 30 base.

In witness whereof I have hereunto signed my name this 2nd day of April 1913, in the presence of two subscribing witnesses.

MAXIMILIAN ROBERT LAWRENCE.
